APPARATUS FOR THE MANUFACTURE OF
THREAD OR THE LIKEHayden B. Kline, Lakewood, Ohio, assignor to
Industrial Rayon Corporation, Cleveland, Ohio,
a corporation of Delaware

Application May 3, 1938, Serial No. 205,864

3 Claims. (Cl. 18—8)

This invention relates to apparatus for the manufacture of thread or the like, particularly apparatus for the production by a continuous process of artificial silk thread. Among other advantages, the apparatus of the present invention provides a particularly simple form of construction which, in that it occupies comparatively little area, serves in large measure to conserve floor space. In use, all parts of the machine are readily accessible for maintenance, replacement and repair, as well as for inspection and manipulation of the thread or the like.

In general, the apparatus of the present invention comprises two upwardly extending banks of vertically stacked thread-advancing thread store devices. Each bank preferably includes one or more series of thread-advancing thread store devices so disposed that the thread or the like, after having been withdrawn from the coagulating bath in which it is formed, is caused, while being subjected to processing treatment, to travel in sequence from device to device. Upon each thread-advancing thread store device, a considerable length of thread or the like is continuously but temporarily stored in the form of a traveling helix made up of a large number of closely spaced, generally helical turns.

While the apparatus of the invention is equally capable of use in connection with the manufacture of artificial silk thread or the like by any of the known processes; e. g., the viscose, cuprammonium, nitrocellulose and cellulose acetate processes, for convenience it is illustrated in the accompanying drawings and will be hereinafter described as employed in the production and processing of viscose artificial silk thread. In such drawings, Figure 1 is an end elevation of the apparatus, partly in section, along line 1—1 of Figure 2. Figure 2 is a partial front elevation along the line 2—2 of Figure 1. Figure 3 is a front elevation of one of the thread-advancing thread store devices employed in the apparatus of the invention. Figure 4 is a section with parts in elevation, along line 4—4 of Figure 2.

In Figures 1 and 2 of the illustrated embodiment of the invention, each thread 5 is formed by the extrusion of viscose from the spinneret 6 in the coagulating bath 7 contained in the trough 8. The thread 5 is withdrawn from the coagulating bath 7 by winding it upon a thread-advancing thread store device 9 upon which said thread is advanced to a point beyond the edge of the trough 8 and passes downward to the first of a series of similar devices which are designated by reference characters 10 to 18, inclusive. Each

device in the series 9 to 18, inclusive, is adapted to receive the thread led to it, continuously but temporarily store the thread, and positively advance it lengthwise thereof in a plurality of closely spaced, generally helical turns. Thread 5, after being advanced along the last device of the series, passes to any suitable means for collecting the thread, such as the cap-twister 19.

The thread-advancing thread store devices may take any of several suitable forms, but are preferably thread-advancing reels of the type illustrated in Figures 3 and 4. Reels of this type are advantageously employed in the apparatus of the present invention because their construction is such as to permit their support from one end only, leaving their front ends free and unobstructed. In addition to the fact that the front ends of all reels are presented to a common front, the reels are so arranged in what may be called vertically stacked relation that the elements of each reel are directly beneath the corresponding elements of each preceding reel in the same series, the result of such arrangement being that the apparatus as a whole occupies a relatively small amount of floor space.

Referring now to Figures 3 and 4, the typical reel illustrated as capable of being advantageously employed in the present invention is generally of the type shown, described and claimed in copending application Serial No. 652,089, filed January 16, 1933, by Walter F. Knebusch (Patent No. 2,210,914). The reel comprises two rigid, generally cylindrical members 20 and 21, of which member 20, which is referred to as the concentric member, is mounted concentrically upon and for rotation with drive shaft 22. Member 21, which is known as the eccentric member, is rotatably mounted with its axis slightly offset from and inclined to that of the concentric member 20. The periphery of concentric member 20 includes a plurality of longitudinally extending bar members 23 which alternate with an equal number of similar bar members 24 forming the periphery of eccentric member 21.

Concentric member 20 may comprise a cylindrical body portion 25 which serves to support and lend rigidity to bar members 23. Although there are various means for mounting said concentric member, a cap nut 27 may be employed to hold said member 20 against a suitable shoulder on drive shaft 22. Said concentric member 20 may be made to rotate with the shaft 22 by means of a pin 28 inserted through said shaft and seating in a slot 29 in the hub of concentric member 20. Thus concentric member 20 con-

sists essentially of a rigid cage member fixedly mounted upon shaft 22.

Eccentric member 21 may take the form of a rigid cage member, being preferably made up of bar members 24 provided at their outer ends with an internal annular reinforcing ring 31 and at their inner or driving ends with an external annular reinforcing ring 32 by means of which the eccentric member 21 is concentrically mounted upon an annular supporting member 33. Said annular supporting member 33 is rotatably mounted on frame member 34 with its axis in spaced and inclined relationship with respect to the axis of concentric member 20. Drive shaft 22 may, as shown, be journalled in frame member 34. A flexible sealing means 35 may be provided for the purpose of preventing corrosive processing liquids from attacking the bearings and other metal surfaces.

When the shaft 22 is rotated, concentric member 20, being mounted upon and fixed thereto, rotates therewith. Eccentric member 21 is rotated by contact between the interdigitating bar members 23 and 24 of concentric member 20 and eccentric member 21, respectively. As the reel rotates, the offset relation of the bar members 23 and 24 of the members 20 and 21, respectively, causes the thread to be supported first by the bar members of one of the cage members and then by the bars of the other. The inclined relationship between the two cage members causes the thread to advance longitudinally of the reel from the supported to the unsupported end thereof in a large number of closely spaced, generally helical turns.

All of the reels shown in the apparatus of Figures 1 and 2 operate in the same manner and are of the same general type as that disclosed in Figures 3 and 4. Preferably they are mounted as shown in Figure 4 with their axes extending very nearly horizontally; i. e., substantially perpendicularly to a vertical plane parallel to the operating face of the machine. In the illustrated embodiment of the invention, the reels are not strictly speaking horizontally mounted, since they are tilted upward at a small angle to obtain countercurrent flow of the respective processing liquids. If desired, however, the reels could to advantage be mounted horizontally with their axes in parallel planes.

The illustrated embodiment of the present invention, as indicated in Figure 2, contemplates a plurality of thread-producing units which may be disposed longitudinally of the machine along opposite sides of a common coagulating trough 8. A single continuous multiple filament thread is formed and processed by each unit of the apparatus, such unit comprising the spinneret 6 with its associated mass tube 42 and spinning pump 43, a series of vertically stacked reels 9 to 18, inclusive, collecting device 19, etc. Corresponding parts of adjacent similar units are in corresponding positions, which serves also to simplify the construction and operating requirements of the apparatus.

Because of the vertically stacked relation of the reels, it is convenient to place two banks of reels back to back with their free ends facing opposite fronts. Although the vertical arrangement of reels may lend itself to many different forms of apparatus and framework, the type illustrated in the accompanying drawings represents a simple and practical construction. The frame consists mainly of two vertical beams 37 with upper, intermediate and lower cross beams 38, 39 and 40,

respectively. Similar frame members are disposed at either end of the machine and at intervals along the machine and serve to support therebetween a plurality of processing units.

5 The uppermost cross beam 38 serves to support the longitudinal channel 44 which in turn supports gear boxes 45. Drive shafts 46 extend longitudinally of the machine from a driving means (not shown) driving the uppermost reels 9 in each series by means of gearing in the several gear boxes 45 in which the shafts are journalled. The spinning pumps 43 for each series are actuated by longitudinally extending drive shafts 47 disposed on either side of the machine. The viscose is fed to spinning pumps 43 from supply pipes 48 running lengthwise and on either side of the machine. Supply pipes 48 and drive shafts 47 are supported by brackets 49 mounted on the upright frame members 37.

20 Brackets 49 serve to support apron 51 and waste trough 50. At spaced intervals along the length of the machine between trough 8 and the waste trough 50 are provided vertically extending channels 52 for the purpose of guiding the thread 5

25 from the discharge end of reel 9 directly above the entrance to said channel 52 to the reel 10 and the succeeding reels in the series to complete the processing of the thread. The thread thus follows a descending path from reel 8 at the top to reel 18 at the bottom of the series. Intermediate cross beams 39 carry the longitudinally extending stringers 53 which support the trough 8. Each cross beam 39 extends on either side of the trough 8 beyond the vertical members 37 and serves to support a working platform 54 and hand rail 55 on either side of the machine. Lower platforms 102 with hand rails 101 are supported as shown by horizontal stringers 103 and vertical supports 104. Platforms 54 and 102 permit the

30 operators to inspect the reels, spinning pumps, mass tubes, spinnerets and other working parts of each thread-producing unit.

35 Channels 61 extend longitudinally of the machine between the spaced frame members made up of the vertical beams 37 and the cross beams 38, 39 and 40 to carry the support brackets or frame members 36, shown in Figure 4.

40 Each series of reels 10 to 18, inclusive, supported upon the horizontal channels 61, are driven by means of gears 73 and 74 from the vertical drive shaft 75 which is supported in a vertical position by the bearing brackets 76 and vertical thrust bearings 78 carried by the angles 77 and channels 79, respectively, which are supported by the vertical frame members 37. Each of the vertical drive shafts 75 for each series of reels is driven by the gears 80 and 81 at the lowermost end of each shaft. Gears 81 are driven by the shafts 82 extending the length of the machine on either side thereof and serving to drive the vertical shaft for each series of reels. Sufficient space extending lengthwise of the machine may be left between the vertical shafts to permit workmen to enter and perform such inspection, repair or replacement work as may be necessary.

45 The trough 8 is provided with conduits 56 from which the coagulating liquid is supplied. Drain pipes 57 which are located at spaced intervals along the central axis of the trough communicate with the main drain conduit 58 running lengthwise of the machine. Each drain pipe 57 has its intake at its upper end and is so disposed as to permit the level of the liquid to be constantly maintained in the trough. The bottom 50 of the trough 8 may be provided with a sloping

70

insert 59 extending lengthwise thereof to prevent undue agitation of the bath and also to reduce the volume of liquid necessary to fill the trough to the proper depth.

In the illustrated apparatus, the processing liquid is applied to the thread being stored and advanced upon each of reels 10 to 16, inclusive, by a suitable reagent distributor 62 to which the proper reagent is supplied by the conduits 63 extending lengthwise of the machine and providing reagent to the corresponding reels of adjacent series on the same horizontal level. A suitable trough 64, supported below each horizontal series by longitudinally extending angles 65 secured to the vertical frame members 37, serves to collect the liquid. Each trough 64 may be connected with conduits for carrying the liquid to the sewer unless it is desired to re-use the reagent, in which case the conduit is connected to a suitable recirculating and make-up system.

No reagents are applied to the thread upon either reel 9 or reel 17, the former being simply a holding reel and the latter being provided to permit excess liquid to drip from the thread before passing to drying reel 18.

Various methods may be employed for drying the thread after treatment, but the drying reel 18, which is of the general type shown, described and claimed in prior application Serial No. 129,848, of Alden H. Burkholder, for "Apparatus for drying thread or the like," now Patent 2,189,195, is particularly advantageous. The drying of the thread stored upon the reel is accomplished by heating the reel by means of some heated fluid, in this instance, a heated liquid which passes into a chamber in the interior of the reel through the hollow drive shaft 67 from a fitting 68 supplied from the inlet conduit 69 which runs the length of the machine. The drying medium after circulating through the reel chamber is returned to the fitting 68 and thence to the outlet conduit 70 which, like inlet conduit 69, runs the full length of the machine and serves a plurality of drying reels. The drying reel 18 may be surrounded by an enclosure 72 which serves to retain the heat.

After being dried upon the drying reel 18, the thread 5 next passes to the cap-twisting device 19. The apparatus shown includes lifting rails 86 disposed on either side of the machine which support the bobbin-supporting whirls 87 for a plurality of cap twisters 19. Guide rods 88 fixed to the frame members 37 by brackets 89 serve to guide the traverse beam 90 in transmitting a vertical reciprocating motion to the lifting rails 86. The vertical motion may be imparted to the lifting rails 86 by conventional means shown as including the cam 91, cam lever 92, weights 93 and chains 94.

The whirls 87 are rotated by the motor 97 by means of belt 98 which completely encircles the machine and passes alternately in and out around a whirl 87 and around a presser pulley 98 (Figure 2) freely rotatably mounted on the lifting rail 86 over the entire length of the machine. The presser pulleys 98 serve to insure a positive driving contact of the belt upon the whirls. Compression pulleys 99 secured to the end vertical frame member tend to exert a fixed tension on the belt 96 between the drive pulley of the motor 97 and the whirls 87 as the lifting rail 86 is reciprocated vertically. The cam 91 may be rotatably mounted and operated by the motor 97 through change speed gear mechanism 100. These driving means indicated herein are only

illustrative; as many other suitable methods may suggest themselves to anyone familiar with such apparatus. In the same way various collecting and twisting devices may be adapted to machines of the illustrated design.

In placing the machine as a whole in operation, the thread 5 is led from the spinneret 6 to the supported end of the reel 9, by which it is automatically advanced toward the unsupported end of the reel in a large number of closely spaced, generally helical turns. Upon reaching the unsupported end of the reel 9, the leading end of the thread is caused to pass downward through channel 52 to reel 10, upon which it winds in helical form exactly as in the case of reel 9. On reaching the unsupported end of the reel 10, the leading end of the thread is removed from the reel by the operator, carried through the eye of guide 105, thence brought at an angle to and through the eye of a second guide 106, and thence conducted to the next succeeding reel. This sequence of operations is performed from time to time as the thread passes over the respective reels until finally the leading end of the thread, having been discharged from the drying reel 18, is led by the operator to the cap-twister 19, where the thread is caused to collect in the form of a package.

The apparatus of the instant invention possesses all of the advantages of prior machines adapted to the production of thread or the like by a continuous process in that (a) the thread-advancing thread store devices, preferably reels of cantilever type, are all presented in two oppositely disposed banks with their free ends unobstructed and facing the operators; (b) working platforms are provided to insure to operators safety and ease of operation, inspection and maintenance; and (c) only a minimum amount of skilled labor is necessary to operate the apparatus. In addition to the aforementioned advantages, an important added advantage is found in the fact that apparatus of the type illustrated occupies a minimum amount of floor space as compared with other machines designed to accomplish the same or similar results.

Thus a machine substantially of the design indicated in the accompanying drawings requires only approximately one-half the room necessary for any other type of machine for producing viscose artificial silk thread by a continuous process. This saving of space becomes of very vital importance when consideration is given to the fact that most commercial plants involve installations of from 50 to 100 such machines to produce the desired output. A substantial saving in the amount of floor space per machine means a correspondingly great saving in cost of construction of buildings in which to house such equipment. It is readily apparent, therefore, that all of the advantages afforded by machines of present design are provided in the apparatus disclosed herein as well as the extremely important space-saving factor and simplification of construction with attendant reduction of cost in building both plant and machinery for commercial use.

As has been previously indicated, the embodiment of the disclosed invention is only illustrative and is capable of various changes or modifications without departing from the spirit of the invention. It should further be understood that the invention is not limited to the manufacture of viscose artificial silk thread, but is applicable to the production and/or treatment of thread or

any thread-like articles which may be manufactured according to a continuous process. It is intended that the patent shall cover, by suitable expression in the appended claims, whatever features of patentable novelty reside in the invention.

What is claimed is:

1. Apparatus for handling thread or the like comprising a source of thread or the like; a concatenate series of thread-advancing reels of cantilever construction arranged to face in the same general direction each of which operates to advance the thread or the like toward the unsupported end thereof in a plurality of substantially helical turns, said reels being individually inclined from the horizontal in such manner that the thread-discharge end of each is higher than the thread-receiving end thereof but nevertheless superposed in such manner that their

vertical projections coincide; guide means between adjacent reels; and, in proximity thereto, collecting means to which thread or the like from said source proceeds after traversing said series of reels.

2. Apparatus as in claim 1 including guide means between adjacent reels in which thread or the like being advanced by adjacent reels is caused by said guide means to reverse its direction of travel in proceeding from the first to the second of said reels.

3. Apparatus as in claim 1 including guide means between adjacent reels in which thread or the like which is proceeding between adjacent reels passes over guide means at the thread-discharge end of the first and other guide means at the thread-receiving end of the second of said reels.

HAYDEN B. KLINE.
